UNITED STATES PATENT OFFICE

171,282

CHENILLE FABRIC

Roy J. Kinsey, Dalton, Ga.

Application March 28, 1950, Serial No. 8,817

Term of patent 14 years

(Cl. D92—2)

To all whom it may concern:

Be it known, that I, Roy J. Kinsey, a citizen of the United States, residing at Dalton, in the county of Whitfield and State of Georgia, have invented a new, original, and ornamental Design for a Chenille Fabric, of which the following is a specification, reference being had to the accompanying drawing, forming part thereof, and in which

The figure is a plan view of a chenille fabric, showing my new design.

The characteristic feature of the design comprises the offset diamond shaped figures, each figure being composed of smaller diamond shaped figures, the offset diamond shaped figures being located at the cross-over points of the wide, slightly overlapped serpentine curves and resulting from the continuation of the elements of said curves, as shown.

A portion of the chenille has been omitted from Figure 1 for convenience of illustration.

I claim:

The ornamental design for a chenille fabric, as shown and described.

ROY J. KINSEY.
